UNITED STATES PATENT OFFICE.

RALPH H. PIERCE, OF EUGENE, OREGON.

MAGNETO-COUPING.

1,301,002.

Specification of Letters Patent. Patented Apr. 15, 1919.

Application filed August 29, 1918. Serial No. 251,937.

To all whom it may concern:

Be it known that I, RALPH H. PIERCE, a citizen of the United States, and a resident of Eugene, in the county of Lane and State 5 of Oregon, have invented a new and Improved Magneto-Coupling, of which the following is a full, clear, and exact description.

This invention relates to an impulse coupling adapted for use in connection with a magneto to produce a hot spark at slow engine speed, as when the engine is being cranked, thereby enabling the largest engines to be started on the magneto without 15 the use of batteries.

The invention has for its general objects to improve and simplify the construction and operation of devices of this character so as to be reliable and efficient in use, comparatively simple and inexpensive to manufacture, and so designed as to be automatic in operation.

A more specific object of the invention is the provision of an impulse coupling of 25 that type embodying a spring between the two sections of the coupling, with automatic dogs for holding the armature section of the coupling restrained while the spring is placed under tension by the turning of the engine crank in starting, and when the dogs are automatically released the spring imparts a quick impulse to the armature shaft, whereby a hot spark is produced to ignite the gas in the cylinders, the 30 dogs having automatic means for throwing them out of operative position when the engine turns at high speed under the explosive impulses, and also having means for restoring the dogs when the engine stops, 35 so that the dogs will be ready to perform their function when the engine is again cranked.

With such and other objects in view, the invention comprises various novel features 45 of construction and arrangement of parts which will be set forth with particularity in the following description and claims appended hereto.

In the accompanying drawings, which 50 illustrate one embodiment of the invention and wherein similar characters of reference indicate corresponding parts in all the views,

Figure 1 is a view of the magneto with 55 the coupling applied;

Fig. 2 is a similar view showing the dogs

engaged while the spring is being placed under tension;

Fig. 3 is a side view of the coupling; and

Fig. 4 is a central vertical section on the line 4—4, Fig. 1.

Referring to the drawing, A designates a magneto which may be of the high or low tension type and adapted for use in connection with an engine having any desired number of cylinders, and to the armature shaft 1 is attached the impulse coupling B, which is connected in any suitable manner with the engine shaft 2.

The coupling B is composed of an engine section 3 and an armature shaft section 4 of any suitable construction, the section 3 being in the form of a cap having a diametrical key lug 5 for engagement with the slotted 65 head or member 6 of the engine shaft 2, and projecting from the periphery of the section 3 are stop lugs 7 each having a cam surface 70. The section 4 is in the form of a ring having a central hub 9 in which is keyed the 75 armature shaft 1, and surrounding the hub is a cylindrical boss or wall 10 which loosely extends into the cap section 3. A helical torsional spring 11 is housed in the boss 10 and has opposite ends 12 and 13 connected with 80 the sections 3 and 4 of the coupling, so that by relative rotation of the sections the spring 85 is placed under tension. On the section 4 and pivoted at diametrically opposite points 14 are dogs 15 having trailing arms 16 each 90 provided with a weight 17. On the magneto frame is a notch, shoulder or projection 18 with which the dog 15 is adapted to engage 95 in order to hold the section 4 of the coupling stationary while the spring 11 is being wound or placed under tension, and after the section 3 is rotated a suitable number of degrees the cam surface 8 of the nearest projection will engage the weighted end 17 and tilt the arm 16 so as to disengage the dog 100 15 from the projection 18. In Fig. 3 this action is about to take place, and as soon as the releasing is completed the tension of the spring 11 causes the section 4 of the coupling 105 to rotate with a very quick impulse, whereby the armature of the magneto is caused to turn at such a speed as to produce a hot spark in the engine cylinder. The explosion now taking place will cause the engine shaft to rotate at a high speed and the weighted arm 110 16 fly outwardly by centrifugal action, so that the dogs 15 are held retracted inwardly.

so as not to engage the projection 18. Suitable means, such as springs 19, act on the arms 16 to normally hold the weight 17 inwardly and the dogs 15 outwardly, as when the engine is idle. When the dog is released 5 from the projection 18 the section 4 of the coupling is thrown forwardly under the tension of the spring through a slight angle until the projections 20 on the section 4 strike the projections 7, but this movement is so quick that the current generated by the magneto is sufficient to produce a hot igniting spark.

From the foregoing description taken in 15 connection with the accompanying drawings, the advantages of the construction and method of operation will be readily understood by those skilled in the art to which the invention appertains, and while I have described 20 the principle of operation, together with the device which I now consider to be the best embodiment thereof, I desire to have it understood that the device shown is merely illustrative and that such changes may be 25 made when desired as fall within the scope of the appended claims.

Having thus described my invention, I claim as new and desire to secure by Letters Patent:

30 1. A coupling of the class described, com-

prising two relatively rotatable sections, one of the sections being provided with lugs having cam surfaces on one face and the other section with projections, a spring connecting the sections, pivoted and spring pressed dogs 35 mounted on the section having the projections, said dogs having curved and weighted arms adapted to be engaged by the cam surfaces of said lugs, and a fixed projection with which the dogs engage, a projection being 40 adapted to engage the face of a lug opposite that having a cam surface when the dog is disengaged from the fixed projection.

2. A coupling of the class described, comprising a cap-like section provided with lugs 45 having cam surfaces on one face, a second section having a cylindrical boss fitting in the cap and provided with projections, a spring in the said boss and having its ends secured to the sections, pivoted and spring 50 pressed dogs mounted on the second section at the projections, said dogs having arms provided with weights at their ends adapted to engage the cam surfaces of the lugs, and a fixed projection with which the dogs engage, the face of a lug opposite the cam surface being adapted to engage a projection when the dog is disengaged from the fixed projection.
